UNITED STATES PATENT OFFICE.

EUCLID ANDERSON, OF PEEKSKILL, NEW YORK.

RATCHET-DRILL.

SPECIFICATION forming part of Letters Patent No. 316,321, dated April 21, 1885.

Application filed November 28, 1884. (No model.)

To all whom it may concern:

Be it known that I, EUCLID ANDERSON, a citizen of the United States, residing at Peekskill, in the county of Westchester and State of New York, have invented an Improvement in 5 Ratchet-Drills, of which the following is a specification.

This invention relates to self-feeding ratchet-drills, and is a modification of the kind in 10 which a differential ratchet is used to effect the feed.

In said devices as heretofore used the feed is apt to be very irregular, because uniformity of feed depends on the relative position of the 15 pawls at the beginning of the stroke, for if the feed-pawl does not fall into its place in advance of the drill-pawl either no feed or only a slight feed (according as the teeth in the ratchet are coarse or fine) occurs; hence it is 20 necessary to watch the ratchets at every stroke to secure regularity, and therefore if the drill is used in a position where the pawls cannot be seen, the feed action is very uncertain.

The main object of my invention is to provide 25 a feeding device that will be positive and proportional to the movement of the drill, no matter how great or little the throw of the ratchet; and a secondary object is to have the feed so arranged that it can be operated independently 30 of the feeding device, the same as in the old form of drill. I attain these objects, the first by using instead of differential ratchets, differential gearing, in combination 35 with the drill-ratchet, and the second by adding a milled collar to the threaded sleeve forming the nut, all of which is more clearly shown in the accompanying drawings, in which—

Figure 1 is a side view, partly sectional, of 40 a drill embodying my invention. Fig. 2 is an end view of the left-hand end of Fig. 1. Fig. 3 is a view of the right-hand end of Fig. 1 with the part C C', sleeve F, and screw E removed.

Similar letters refer to similar parts throughout 45 the drawings.

A is the drill-spindle.

B is the handle or lever, which at one end is formed into the yoke B' C', the part B' forming the bearing for the spindle A.

D is the drill-ratchet rigidly attached to A, and operated by the pawl d and spring S in 50 the usual manner.

F is a threaded sleeve in line with the spindle A, and having bearing in the branch C C' of the yoke. This sleeve abuts against the 55 spindle, and through it passes the screw E, whose outer end is provided with a suitable center, and whose inner end enters a chamber in the spindle A. The spindle and screw are splined together, as in other drills of this class. 60

On a boss of the spindle and adjacent to ratchet D is rigidly secured the spur-wheel I, which forms the "driver" of the differential movement.

J is the intermediate and H is the driven 65 spur-wheel. The latter is either formed on or rigidly fastened to the sleeve F, which forms the nut. The intermediate J finds bearing on the pin K, on which also it is capable of lateral movement, by which means it may be slid 70 into or out of mesh with the driver I, in either case remaining in mesh with wheel H. To retain the intermediate in either of its positions it is provided with a hub, in which is formed the groove n, leaving the flange m. When J 75 is out of mesh with I, as in Fig. 1, a lever, j, pivoted at i, is pushed into the groove n, as in Fig. 1, and holds the intermediate in said position. When the intermediate is in its other position, the lever j will enter behind the flange 80 m and retain J, as shown in Fig. 3.

For convenience of construction I make the yoke B' C in two parts and clamp them together by the bolt c.

On the outer end of the threaded sleeve F, 85 I form a place or collar, G, which is coarsely milled for hand use or drilled for a spanner, or both, by which the screw can be worked in or out independently of the gearing, when I and J are disengaged, as in position of Fig. 1. 90

The use of differential gearing in drills not being new, it will not be necessary to explain their action; but what has been shown of their employment here will make it clearly seen that with this arrangement, so long as the 95 spur-wheels are all in gear, no movement forward of the drill-ratchet or driving device can take place without a proportionate advance of the feed. No matter, therefore, how long or how short the throw of the handle, the feed must 100 be uniform.

If it is necessary to advance or retract the screw, the intermediate J is shifted laterally till it is out of mesh with I, and then by means

of the collar G the screw may be worked at will.

I make no claim to the threaded sleeve and splined screw and spindle; neither do I claim 5 the use of differential gear for actuating drill-feed, as I am aware of its use in connection with a traversing threaded spindle, as in several patents and in one to myself, No. 271,290; but I am not aware of its previous use in connection with a ratchet-spindle and splined feed-screw.

What I claim, and desire to secure by Letters Patent, is—

1. In a ratchet-drill, the combination, with 15 the splined spindle and screw A and E and threaded sleeve F, of the differential spur-wheels H

I J, one attached to the spindle, one attached to the threaded sleeve F, and one acting as intermediate, all operating together to effect the feed, substantially as shown.

2. In a ratchet-drill, the combination, with 20 the splined spindle and screw A and E, and threaded sleeve F, of the differential feed-gear H I J, pawl or lever j, for retaining intermediate in position, and the milled collar G, for independent feed, all operating together substantially as shown.

EUCLID ANDERSON.
